(57) **CLAIM**

I claim the ornamental design for an American flag hat, as shown.

DESCRIPTION

FIG. 1 is a perspective view of the hat, showing my design; FIG. 2 is a front elevational view of the hat; FIG. 3 is a right side elevational view; FIG. 4 is a left side elevational view; FIG. 5 is a rear elevational view; and, FIG. 6 is a top plan view.

The broken line showing of the top button in FIG. 1 is for illustrative purposes only and forms no part of the claimed design.
